MARLEY FOTHERINGHAM HAY AND FERDINAND GUHRAUER, OF DUMBARTON,
SCOTLAND.

SUBMARINE OR SUBMERSIBLE BOAT.

1,107,942.

Specification of Letters Patent. Patented Aug. 18, 1914.

Application filed February 20, 1914. Serial No. 819,986.

To all whom it may concern:

Be it known that we, MARLEY FOTHERINGHAM HAY, a subject of the King of Great Britain and Ireland, and FERDINAND GUHRAUER, a subject of the King of Hungary, residents of Dumbarton, Scotland, have invented certain new and useful Improvements in Connection with Submarines or Submersible Boats, of which the following is

10 a specification.

The invention has for its object to provide means such that a submarine or submersible boat may continue to be driven by its internal combustion engines or by steam engines (hitherto only used for surface work) when it is much more nearly submerged than hitherto. Thus the boat may proceed under them until it is much nearer the enemy than hitherto, and thus since the 20 electric motors and storage battery are only used when the boat is entirely submerged, the effective radius of action is much increased. Further, also a submarine or submersible boat may be constructed, according to the invention, in which the diving capability is limited to the amount just set forth, and which therefore is never entirely submerged. Thus it may at all times be driven by internal combustion engines and 30 the electric means with their complication and great weight be dispensed with. Or when the vessel is so arranged that it never becomes entirely submerged, steam engines may be used.

35 According to the invention and in order that the boat may be maintained at the requisite level with the necessary accuracy, there is provided a hydro-plane, adjustable it may be in height, above the vessel and in 40 angle. This plane is at such a height above the vessel that when the vessel is in its desired state of submergence, the plane is just at or just above water level. Immediately the vessel tends to sink, the plane 45 enters the water more or less and acts powerfully to raise it. Means are provided for raising and lowering the plane either manually or by power, and to this end it may very conveniently be carried on the forward 50 end of a frame pivoted at its rear upon the vessel and controlled by a stay arranged between its forward end and the forward part of the vessel—means being provided for operating the stay and for turning the frame 55 about its pivot. The means for controlling

the plane are such that it may be operated from within the vessel—freed that is or set at such an angle that it does not interfere with the use of the usual diving planes for submerged running, so that, that is to say, 60 the change from the semi-submerged running to completely submerged running under electric power, may be made without even momentarily coming to the surface. Instead of one adjustable hydro-plane, a 65 plurality may be provided. The plane may be a thin and plate-like structure, or may be buoyant and of hollow boat-like form.

The usual automatically controlled trunk is provided for the engine, the mouth of 70 that trunk being kept safely above normal sea level by the improved means hereinbefore described for maintaining the boat at a given stage of submergence. The trunk, which is in direct communication with the 75 inside of the vessel, serves, in the case of an internal combustion engine, to admit air to the engine, or as a discharge for the products of combustion in the case of a steam engine, is arranged in an armored superstructure, 80 preferably fish-form in plan, and which may also embrace the conning tower, periscopes and ventilators. It is provided with a valve either operated directly by a float to which water at sea level has access, or operated 85 electrically or mechanically, in which case its operation can be controlled by such a float all in known manner.

The usual steering and diving rudders are 90 used for maneuvering, and usual means may be provided for compensating for that difference in weight and trim due to the displacement by water of the fuel oil as it is used. These means consist of a pump abstracting water from a compensating tank, 95 in or in close proximity to the fuel tank, equal in weight to the difference of weight between the oil used and water replacing it in the fuel tank. Or such a pump may be applied to one of the usual ballast tanks in the same manner, the essence of its function being that the weight of fuel used is replaced by an equal weight of water. It is operatively connected to the fuel pump so as to work in strict consonance with it. Again, it is apparent that when the mouth of the trunk is automatically closed by its valve, the engine must draw its air from within the vessel. In order that this air may not be used to too great an extent, the mechanism 100 105 110

which operates the air valve is so interconnected with the fuel-controlling mechanism of the engine that when the valve closes the engine is slowed down to any desired extent. 5 Alternatively, the plane or planes may be fixed in position, and when this is the case, the usual diving rudders are dispensed with and the boat's submergence limited to that attained with the fixed plane or planes, that 10 is to say with its periscopes and ventilator casing or conning tower above water level. As when this is the case, owing to the provision of the improved devices, the internal combustion engines or steam engines may 15 still be used for propelling, the electric propelling machinery with its complication and weight may be dispensed with. Thus according to the invention there may be constructed a much lighter, speedier, simpler, 20 and cheaper boat than hitherto possible sufficiently submersible for its protection from gun fire.

In order that the invention and the manner of performing the same may be properly 25 understood there are hereunto appended four sheets of explanatory drawings in which is shown in sectional elevation, with the mechanism respectively in the open and in the closed position, in Figures 1 and 2, 30 Sheet 1, and in plan in Fig. 3 an example of the trunk, valve, and controlling gear. In Fig. 4, Sheet 2, is shown another like example of this mechanism. In Fig. 5, Sheet 3, and Fig. 6, Sheet 4, is shown in elevation 35 and plan respectively a like example of the improved plane, and in Fig. 7, Sheet 2, a detail thereof. In Fig. 8, Sheet 3, and Fig. 9, Sheet 4, is shown respectively a diagram of the pump controlling mechanism and a 40 sectional elevation of a form of controlled pump.

The example of the improved semi-submergence maintaining plane, which may either be a plane in the true sense, or be 45 curved in profile, and which is shown in Figs. 5, 6 and 7, consists of a framing 26 pivoted at its rear end on a transverse pivot 27 on the boat. At its outer end the plane 28 itself is pivoted on a shaft 29 near its 50 leading edge. For depth-maintaining purposes it is retained against the frame by fingers 30 on sliders 31 on the side members of the frame. These sliders are connected by links 32 with levers 33 on the pivot shaft 27, 55 which levers are operable by worm gearing 34 to retract the fingers and so release the plane 28, upon which being done the plane floats free, as indicated by dotted lines in Fig. 6, and with no effect in maintaining the 60 boat's level. The plane is preferably arranged to be raised to the desired angle, or lowered flush with the structure from within the boat. In the present example, the mechanism to accomplish this consists of a compressed air operated piston in a cylinder 35

and the rod 36 of which is connected to a lever 37 rigidly fixed to the framing 26, and coacting therewith a hawser 38 attached to the outer end of the framing and passing within the boat where it may be paid out or 70 hauled in more or less to adjust the angle or to bring the frame to the flush. In order that the round cross members of the framing 26 may not create objectionable eddy currents when submerged, they may have freely 75 strung upon them fish-form pieces 39 of wood or the like. These are shown separately in Fig. 7.

It is to be understood, firstly, that a plane or a number of them of the adjustable type 80 just described may be placed in any convenient and effective position or positions on the boat. Secondly, that alternatively the plane or planes may be fixed in the case as hereinbefore explained of a boat never intended to be more submerged than that degree of controlled submergence which the plane permits. Thirdly, that the area of the plane (or of the planes as a whole) and their angle is such that they normally control the 90 level of the boat before their complete submergence takes place—that is to say, their area and angle jointly is in excess or in the direction of excess of what is necessary to preserve the definite level of the boat. And 95 fourthly, the plane or planes may be either of plate-like or buoyant and boat-like form.

With the improved means for maintaining the boat at a given stage of submergence, it is necessary to provide a trunk above normal 100 water level, serving to admit air to an internal combustion propelling engine, or serving as a discharge for the products of combustion in the case of a steam engine, and to provide means for controlling the mouth of the trunk. In an example of trunk control 105 shown in Figs. 1, 2 and 3, the trunk 1 is carried considerably above the level of the top of the vessel. It is inclosed in a casing 2 fish-form in plan and to which the water 110 has free access. The inlet of air to the trunk 1 is controlled by a valve 3 pivoted on a bracket 4 at the mouth of the trunk upon which the valve seats. From the valve there extends a lever arm 5 connected by a rod 6 to the piston rod 7 of a piston 8 in a double acting compressed air operated cylinder 9. An ordinary slide valve 10 controls the supply of air to both sides of the piston 8, and its rod 11 is connected to a lever 12 on a shaft 13 which has also on it a second lever 14 upon which is a float 15, all in known manner. As already explained, the engine may be so interconnected with this valve mechanism that its speed is reduced to a 125 minimum upon closure of this valve. To this end, and as diagrammatically illustrated in Fig. 1, a system of links and levers 16 may be arranged between the rod 6 and a pusher 17 adapted to move the engine con- 130

trol lever 18 to the reduced speed position when the valve 3 closes.

In operation, the float 15 is normally in the position shown in Fig. 1 and the valve 3 open. Immediately a surge of water lifts the float, it, through the levers 14, 12, operates the air valve 10 which admits air beneath the piston 8 which then rises and closes the valve. As soon as the float falls again, the air valve 10 is moved to admit compressed air above the piston 8, and the valve 3 is then immediately opened. Simultaneously, control of the engine takes place through the linkage 16. Alternatively, and as shown diagrammatically in Fig. 4, the control may be electrical instead of by float. In this example, contact plates 19, 20, controlling the circuit of a solenoid coil 21, become submerged when a surge of water occurs, they being sufficiently closely placed, the water acts as an electrolyte completing the circuit. The coil 21 being then energized pulls down the solenoid 22 against the action of a spring 23. The solenoid is connected by a link 24 to a rocking lever 25, which in turn is connected to the air valve 10 which it thus operates to admit air to the cylinder 9 and so operate the valve 3 in substantially known manner.

In order to obtain the best results, it is well as already explained that means should be provided for the difference in trim and weight due to the difference in specific gravity of the water gradually displacing the fuel oil in the fuel tanks. Means to this end are shown in Figs. 8 and 9. In this arrangement which is of substantially known form, there are two pumps, one large pump 40, the fuel pump, and one small pump 41, the compensating pump, and the capacity of the compensating pump is to the capacity of the fuel pump as the difference between the weight of fuel oil and a similar volume of sea water is to the weight of the fuel oil. In Fig. 8 the compensating pump is shown pumping from a small tank 42 whose capacity is at least so great that it may contain water of a weight equal to the difference between the weight of the fuel in the tank 43 and the same tank full of water, and whose center of gravity when full it is desirable to keep as close to the center of gravity of the fuel tank when full as possible, but the pump may pump if convenient from any tank of the vessel whatsoever. In the arrangement shown, the fuel pump 40 has its inlet 44 from the top of the fuel tank 43, and its delivery 45 to the engine. To the bottom of the fuel tank is a sea connection 46. The compensating pump 41 has its inlet 47 from the bottom of the compensating tank, while its delivery 48 is overboard. To control the speed of the engine, the capacity of the fuel pump is varied, and in order that perfect compensation occur, it is necessary

to vary the capacity of the compensating pump in exactly the same way. This is arranged for in the present instance by making the pumps exactly similar in construction, driving both pumps from the same shaft, and governing both from the same handle. Fig. 9 shows the general arrangement of a pump, and more particularly the regulating device. On the driving shaft 49 is fitted an eccentric and rod 50, and on the governing shaft 51 turned by a handle 52, another eccentric and rod 53 both of which actuate the floating link 54 which in turn actuates the rod 55, and hence the inlet valve 56. As will be seen from Fig. 9, when the handle 52 is moved the shaft 51 is rotated and actuates the rod 55 through the link 54 and the eccentric and rod 53, thus causing the inlet valve to remain open a longer or shorter period as desired after the pump 50 plunger has started upon the delivery stroke. In practice the compensating tank 42 is filled when the ballast tanks are filled for submerging. The engine is then started and the compensating pump then begins to draw water from its tank.

What we claim is:—

1. In a submarine or submersible boat, means for maintaining the boat at a given stage of submergence consisting of a plane structure so placed and at such a height above the boat's main structure that it acts automatically as a hydro-plane when the boat is submerged to a depth to bring it into contact with the water, a trunk, and means for automatically controlling the mouth of the trunk in accordance with the local rise and fall of the surface level.

2. In a submarine or submersible boat, means for maintaining the boat at a given stage of submergence consisting of a plane, a framing to which the plane is pivoted, this framing being pivoted at its rear end on the boat's structure, a motive fluid cylinder and piston, links connecting the piston rod thereof to the frame, sliders on the side members of the frame, fingers on the sliders holding the plane in position, levers on a pivot shaft, links connecting the sliders with these levers, worm gearing operating the levers to retract the fingers and so release the plane, a trunk, and means for automatically controlling the mouth of the trunk.

3. In a submarine or submersible boat, means for maintaining the boat at a given stage of submergence consisting of a plane, a framing to which the plane is pivoted, this framing being pivoted at its rear end on the boat's structure, a motive fluid cylinder and piston, links connecting the piston rod thereof to the frame, sliders on the side members of the frame, fingers on the sliders holding the plane in position, levers on a pivot shaft, links connecting the sliders with these levers, worm gearing operating the levers to retract the fingers and so release the plane, a trunk, and means for automatically controlling the mouth of the trunk.

- levers to retract the fingers and so release the plane, a trunk, means for automatically controlling the mouth of the trunk, and means for maintaining trim and constant weight 5 irrespective of the consumption of oil fuel.
4. In a submarine or submersible boat, means for maintaining the boat at a given stage of submergence, a trunk, means for automatically controlling the mouth of the 10 trunk, means for maintaining trim and constant weight irrespective of the consumption of oil fuel, and means for controlling the speed of the engine in accordance with the control of the mouth of the trunk.
- 15 5. In a submarine or submersible boat, means for maintaining the boat at a given stage of submergence consisting of a plane, a framing to which the plane is pivoted, this framing being pivoted at its rear end on 20 the boat's structure, a motive fluid cylinder and piston, links connecting the piston rod thereof to the frame, sliders on the side members of the frame, fingers on the sliders holding the plane in position, levers on a pivot 25 shaft, links connecting the sliders with these levers, worm gearing operating the levers to retract the fingers and so release the plane, a trunk, means for automatically controlling the mouth of the trunk, means for maintaining 30 trim and constant weight irrespective of the consumption of oil fuel, and means for controlling the speed of the engine in accordance with the control of the mouth of the trunk.
- 35 6. In a submarine or submersible boat, means for maintaining the boat at a given stage of submergence, a trunk, the top of which is above normal water level, and by which air is admitted to an internal combustion engine, or by which the products 40 of combustion from a steam engine are discharged, means for automatically controlling the mouth of the trunk, means for maintaining trim and constant weight irrespective of the consumption of oil fuel, and means for controlling the speed of the engine in accordance with the control of the mouth of the trunk.
- 45 7. In a submarine or submersible boat, 50 means for maintaining the boat at a given stage of submergence, a trunk, means for automatically controlling the mouth of the trunk consisting of a valve, a motive fluid cylinder and piston operatively connected thereto, a valve controlling the supply of 55 fluid to the cylinder, a float operatively connected to the latter valve and so placed that it moves with the rise and fall of the surface level adjacent to the mouth of the trunk, means for maintaining trim and constant weight irrespective of the consumption of oil fuel, and means for controlling the speed of the engine in accordance with the control of the mouth of the trunk.
8. In a submarine or submersible boat, 60 means for maintaining the boat at a given stage of submergence, a trunk, means for automatically controlling the mouth of the trunk, means for maintaining trim and constant weight irrespective of the consumption of oil fuel consisting of a fuel pump and a second pump which has an output proportional to that of the fuel pump, a fuel tank, a small compensating tank placed in the fuel tank out of which water is 65 pumped in such quantities as to compensate for the difference in weight between the oil consumed at any time and the sea water taking its place, and means for controlling the speed of the engine in accordance with 70 the control of the mouth of the trunk.
9. In a submarine or submersible boat, means for maintaining the boat at a given stage of submergence, a trunk, means for automatically controlling the mouth of the 75 trunk, means for maintaining trim and constant weight irrespective of the consumption of oil fuel, and means for controlling the speed of the engine in accordance with the control of the mouth of the trunk consisting of an engine control lever, a pusher 80 adapted to move the engine control lever, and a system of links and levers so arranged between the pusher and an extension of the piston rod so that when the valve controlling the mouth of the trunk closes the engine control lever is moved to the reduced speed position.

In testimony whereof we have signed our names to this specification, in the presence 100 of two subscribing witnesses.
